C. Hughes
by *John J. Hughes*
Atty

UNITED STATES PATENT OFFICE.

CECIL HUGHES, OF LLANDRINDOD WELLS, WALES.

FUEL-DELIVERY PUMP FOR INTERNAL-COMBUSTION ENGINES AND OTHER PURPOSES.

Application filed March 7, 1923. Serial No. 623,565.

To all whom it may concern:

Be it known that I, CECIL HUGHES, a subject of the King of England, and residing at Llandrindod Wells, in the county of Radnor, Wales, have invented Improvements in and Relating to Fuel-Delivery Pumps for Internal-Combustion Engines and Other Purposes, of which the following is a specification.

10 This invention relates to means for supplying liquid fuel to internal combustion engines said means being of the kind in which the compression on the fuel is had by means of a plunger pump and suddenly 15 released into a space or chamber containing air, it being however, also applicable to supplying combustible mixtures to heating and other apparatus.

According to the present invention the 20 fuel is induced into the cylinder of a plunger pump, on one side of the plunger by the movement of the plunger in one direction, the return movement of the plunger in the opposite direction serving to exert 25 compression on the fuel thereby induced in and, after a predetermined movement of the plunger in the same direction, to suddenly release the fuel under pressure and permit it to pass through a transfer passage 30 or pipe to the interior of the pump cylinder on the opposite side of the plunger where it commingles with air and from which the mixed air and fuel passes out through a suitably arranged outlet.

35 The invention may therefore be said to consist broadly of liquid fuel supply means comprising a plunger pump by means of which fuel is induced into its cylinder on one side of the plunger by movement of the plunger in one direction the return movement of the plunger in the opposite direction serving to exert compression on the fuel thereby induced in and, after a predetermined movement of the plunger in the same 40 direction, to suddenly release the fuel under pressure and permit it to pass through a transfer passage or pipe to the interior of the pump cylinder on the opposite side of the plunger where it commingles with air and from which the mixed air and fuel passes out through a suitably arranged outlet.

The invention is particularly applicable to that type of pump having an air compression arrangement in connection with the

neck or part of the pump through which the plunger passes.

In this type of pump the air compression arrangement may be utilized to supply air to the interior of the pump cylinder on that side of the plunger to which the suddenly released fuel is passed after being subjected to pressure.

In a reciprocating piston pump, according to one embodiment of this invention, the intake or suction inlet is at a point on the side of the cylinder intermediate its ends; and the delivery conduit is at one end. A communicating pipe connects together two points of the cylinder, through which the liquid is transferred from one side of the plunger to the other in the active stroke of the pump. That is, the liquid drawn into the outer end of the cylinder by the intake or suction stroke of the plunger, is forced in the forcing action of the plunger, out of this end by the plunger through or by way of said transfer pipe, to the opposite or delivery side of the plunger, and air is forced by the compressor which may be of the diaphragm type, into the delivery end of the pump, and the liquid is atomized and the mixture forced to the engine intake conduit, and delivered through a nozzle or the like into it, where it is mixed with the further quantity of air required.

The invention is illustrated in the accompanying drawings, in which:

Fig. 1 is a sectional view illustrating the improvement.

Fig. 2 is a similar view of a modification.

Fig. 3 is a similar view of a further modification.

1 is the pump cylinder, 2 is the pump piston, and 3 is its piston rod. 4 is the intake or suction pipe of the pump, disposed between the two ends of the cylinder, 5 is the delivery pipe entering the cylinder near its end, at which the piston rod 3 is connected to the piston, and 6 is the transfer pipe, communicating with the cylinder at the outer end, and at a point between the points where the suction and delivery pipes or conduits 4 enter the cylinder.

7 is the vessel of the diaphragm compressor, of which 7^x is the air inlet valve, through which the piston rod 3 passes and upon the upper end of which flexible diaphragm 8 is provided, to which the piston rod 3 is connected by a nut or flange 9 in

the known way. In the case shown, the diaphragm is adapted to be operated by an eccentric 11, operating a lever 12, which is connected with the upper end of the piston rod 3.

Communication is provided between the vessel 7 and the top of the pump cylinder, and this may be effected by a slight clearance or space between the piston rod 3 and the upper end of the cylinder 1, and in the diaphragm compression stroke, which is simultaneous with the active piston stroke air is forced to the upper or piston rod end of the cylinder with the effect hereafter described.

In action, assuming the piston 2 to be at the upper end of its stroke, and the diaphragm 8 also at the upper end of its stroke, and they are moved down in their active strokes, when the top of the piston uncovers the upper or port end of the pipe 6, the pressure in the lower end of the pump cylinder will be at its maximum, and owing to its pressure the liquid rushes with great velocity into the space above the piston, which will contain air and atomized petrol, forced down into it through the space between the piston rod 3 and the cylinder head, by the pressure in the chamber 7 created by the diaphragm, which will be greatest at this moment, and it will be broken up or atomized.

After the uncovering of the upper end of the pipe 6 by the piston, and the atomization of the fuel, the fluid by its pressure will be delivered to the intake of the cylinder of the engine, say where the carburettor is usually placed, and supplied with further air as usual. That is, at the moment of release by the piston, and afterwards, the pressure pushes all before it, and forces it to the point of use through pipe 5 as specified.

The pressure in the vessel 7 will also have forced any liquid in the vessel 7 through the pipe 15, which is without a valve back to the petrol supply tank. This pipe 15, being suitably choked somewhat, while it will carry away all liquid which may have reached and deposited in the vessel 7, will have such a pressure in it created by the downstroke of the diaphragm, that air will be forced by it down between the rod and cylinder body, as stated, into the top of the cylinder.

In the return stroke of the pump piston, the fluid in the cylinder above it is partly forced back into the vessel 7 between the piston rod and cylinder head, and partly into the pipe 5.

The delivery of fuel from the pump at the engine is timed to coincide with each induction stroke of the engine, and its final delivery to the engine is through a jet or jets.

In the modification shown in Figure 2,

below the end of the cylinder 1, a spring retained device is provided so that the capacity of the chamber is automatically extensible.

In the case shown, this device consists of a flexible diaphragm 16, normally pressed up by a spring 17 within the casing 18.

This allows for the liquid or fuel to be put under pressure, which when the charge is liberated as above described, reacts on the fluid and continues to react, while it is delivered from one side of the piston 2 to the other, that is follows it up; and thus the moment the transfer port 6 is uncovered by the piston, the strong spring 17 forces the fuel forward from the enlarged cylinder chamber 19, into the top as described.

The tension of the spring 17 is adjustable by a screw support 20 which supports the spring and screws in and out the casing 18.

With reference to the modification shown in Figure 3, there is used in connection with the lower part of the pump, means for admitting a regulated quantity of air, namely, it is provided with a non-return valve 21, and an ordinary regulating cock 22, so that a certain amount of air will be drawn into the pump as well as liquid fuel, which will mix with it, and the two will be delivered through the transfer conduit 6 as above described, and moreover this air inlet will cover or control to a considerable extent the quantity and the degree of vacuum in the lower end of the cylinder on the up or suction stroke of the piston.

By this means, the actual amount of fuel entering the cylinder is controlled, and thereby the actual delivery of any required quantity, both the air and fuel so introduced are compressed together in a state of almost complete atomized fuel.

Further, a non-return valve 23 is provided on the delivery port 5 of the pump; and also a pipe 24 with a non-return valve 25, on it connects the interior of the diaphragm chamber 7 with the top end of the cylinder, so that the air which is drawn into the chamber 7 and compressed on the down stroke of the diaphragm 8 is admitted into the top of the pump cylinder on the downward stroke of the pump piston until the point is reached by the piston at which it lies between the openings of the transfer port 6, whereupon the charge of compressed air and fuel—nearly or wholly atomized—from the lower end of the cylinder rushes through the transfer port with great velocity and meets the compressed air in the outer upper end of the cylinder, and so promoting a higher degree of atomization of the fuel.

The pressure in the top of the cylinder is at its highest immediately the transfer port is uncovered, at which point also the pressure of the air in the diaphragm chamber

What is claimed is:—

1. A fuel supply means including a cylinder having a fuel inlet, a fuel outlet, a plunger operative in the cylinder to draw fuel into the cylinder through the inlet on a predetermined movement of the piston and to exert pressure on the contained fuel in the opposite movement of the piston, means for establishing communication between that portion of the cylinder communicating with the inlet and that portion of the cylinder communicating with the outlet, said means being closed against communication with that portion of the cylinder communicating with the outlet until the piston has reached a predetermined point in its movement and exerted a corresponding pressure upon the fuel in the cylinder, and means for supplying air to that portion of the cylinder communicating with the outlet.
2. A fuel supply means including a cylinder having a fuel inlet, a fuel outlet, a plunger operative in the cylinder to draw fuel into the cylinder through the inlet on a predetermined movement of the piston and to exert pressure on the contained fuel in the opposite movement of the piston, means for establishing communication between that portion of the cylinder communicating with the inlet and that portion of the cylinder communicating with the outlet, said means being closed against communication with that portion of the cylinder communicating with the outlet until the piston has reached a predetermined point in its movement and exerted a corresponding pressure upon the fuel in the cylinder, and means for supplying air to that portion of the cylinder communicating with the outlet.
3. A fuel supply means including a cylinder having a fuel inlet, a fuel outlet, a plunger operative in the cylinder to draw fuel into the cylinder through the inlet on a predetermined movement of the piston and to exert pressure on the contained fuel in the opposite movement of the piston, means for establishing communication between that portion of the cylinder communicating with the inlet and that portion of the cylinder communicating with the outlet.

the inlet and that portion of the cylinder communicating with the outlet, said means being closed against communication with that portion of the cylinder communicating with the outlet until the piston has reached a predetermined point in its movement and exerted a corresponding pressure upon the fuel in the cylinder, and a diaphragm pump operative in the movement of the plunger for supplying air to that portion of the cylinder communicating with the outlet.

4. A fuel supply means including a cylinder having a fuel inlet, a fuel outlet, a plunger operative in the cylinder to draw fuel into the cylinder through the inlet on a predetermined movement of the piston and to exert pressure on the contained fuel in the opposite movement of the piston, means for establishing communication between that portion of the cylinder communicating with the inlet and that portion of the cylinder communicating with the outlet, said means being closed against communication with that portion of the cylinder communicating with the outlet until the piston has reached a predetermined point in its movement and exerted a corresponding pressure upon the fuel in the cylinder, and a diaphragm pump operatively connected with the plunger and serving during the suction stroke of the plunger to draw air into the pump and in the operative stroke of the plunger to force said air into the cylinder in that portion communicating with the outlet.

5. A liquid fuel supply means, including a chamber having an air inlet, a diaphragm operative in the chamber, a pump cylinder connected to and having communication with the chamber, a piston operative in the cylinder and having a fuel inlet end and a fuel outlet end, a bypass from the inlet end of the cylinder to the outlet end thereof, and a piston rod connecting said piston and diaphragm.

In testimony whereof I have signed my name to this specification.

CECIL HUGHES.
